UNITED STATES PATENT OFFICE.

JAMES F. LEAHY, OF BROOKLYN, NEW YORK.

MOTIVE-POWER DEVICE.

Application filed June 29, 1927. Serial No. 202,320.

This invention relates in a general way to motive power devices for converting reciprocatory motion into rotary motion and has for its primary object to provide an improved 5 construction and arrangement of parts in a mechanical movement suitable for embodiment in fluid pressure engines or for use with any power-driven part or parts for transmitting power thereto.

10 One of the objects of my invention is to provide an improved construction for fluid-pressure engines according to which such engines may be economically constructed and operated. Toward the attainment of this object and in its adaptation to an internal combustion motor my invention contemplates a fluid pressure engine in which very lean gaseous mixtures may be used and in which no cooling system is required; wherein the degree 15 of compression imparted to the gaseous mixtures in the cylinder may be regulated independently of the speed of the engine; whereby the fuel-intake and scavenging operations may be carried on under a sustained 20 substantially constant suction; and wherein the use of valve-operating cam mechanism may be avoided.

One of the objects of the present invention is to provide an improved system for controlling 25 the operation of a fluid-pressure engine embodying a reciprocating piston and a power-transmitting rod rotatably connected thereto under the control of said system.

Another object of the invention is to provide 30 an improved light-weight construction for automobiles whereby a high mileage rate may be secured with a low consumption of fuel.

Other and further objects will appear in the specification and be pointed out in the appended 35 claims reference being had to the accompanying drawings which illustrate my invention in an adaptation to an automobile engine. In the drawings.

Figure 1 is a diagrammatic vertical axial 40 section of an automobile engine constructed in accordance with the principles of my invention parts being shown in elevation.

Figure 2 is a section on the line 2—2 of Figure 1.

Figure 3 is a fragmentary section on the line 3—3 of Figure 1.

According to the embodiment of my invention shown on the drawings, a pedestal 1 supports a cylinder 2 for the internal combustion of motive power fluids, said cylinder be-

ing provided with an ignition device 3 and an air inlet 4 which, if desired, may be utilized for starting the engine by the introduction of a supply of compressed air. Preferably, however, I employ the auxiliary starting device to be hereinafter described. A carburetor 5 with a butterfly valve 6 is shown diagrammatically in communication with the interior of cylinder 2 through a port-opening 7.

In the opposite wall of said cylinder and displaced axially with respect to the port-opening 7, is a port-opening 8 which leads to a housing 8^a containing a fan chamber 9, within which operates a fan 10 driven by an electric motor 11. The fan 10 is thus adapted to create a suction through the port-opening 8 and to discharge thru openings 8^b in the rear wall of said housing. An inlet 12 is suitably arranged to supply air to the interior of cylinder 2 for scavenging said cylinder at the end of the piston stroke, said inlet also operating to break the suction on the carburetor until the piston passes the air inlet on its return stroke during which the gaseous mixture is compressed. Reciprocably mounted 75 in the cylinder 2 is a piston 13 within which one end of an endwise-movable rod 14 is rotatably mounted by means of ball bearings 15.

As shown in Figures 1 and 3, the rod 14 is provided with helical ribs 16 which operate in helical guide-ways 17 formed in the hub 18 of a fly-wheel 19, said fly-wheel being supported by ball bearings 20 mounted in axially spaced standards 21, 22. The standards 21, 22 are presented upwardly from a common base plate 23. The forward end of helical rod 14 carries a cross-head block 24, said cross-head block being provided with two pairs of oppositely presented journal pins 25. Journalled upon said pins 25 are rollers 26 which operate between angular guide rails 27 which constitute a cross-head guide mounted on one end of a rotary shaft 28. By means of this construction, helical rod 14 is connected to the rotary shaft 28 by means of an axially slideable non-rotary connection. The rotary shaft 28 may carry a fly wheel 29 which is keyed thereto by a key 30. Said rotary shaft 28 is journalled in a standard 31 and carries a bevel pinion 32 meshing with a bevel gear 33, keyed to the lower end of a short shaft 34, said shaft 34 being rotatably mounted in a bearing block 35 carried by pedestal 31.

Keyed to the upper end of shaft 34 is a bevel gear 36 which meshes with a large bevel gear 37.

Figure 1 is a diagrammatic vertical axial section of an automobile engine constructed in accordance with the principles of my invention parts being shown in elevation.

Figure 2 is a section on the line 2—2 of Figure 1.

Figure 3 is a fragmentary section on the line 3—3 of Figure 1.

According to the embodiment of my invention shown on the drawings, a pedestal 1 supports a cylinder 2 for the internal combustion of motive power fluids, said cylinder be-

ing provided with an ignition device 3 and an air inlet 4 which, if desired, may be utilized for starting the engine by the introduction of a supply of compressed air. Preferably, however, I employ the auxiliary starting device to be hereinafter described. A carburetor 5 with a butterfly valve 6 is shown diagrammatically in communication with the interior of cylinder 2 through a port-opening 7.

In the opposite wall of said cylinder and displaced axially with respect to the port-opening 7, is a port-opening 8 which leads to a housing 8^a containing a fan chamber 9, within which operates a fan 10 driven by an electric motor 11. The fan 10 is thus adapted to create a suction through the port-opening 8 and to discharge thru openings 8^b in the rear wall of said housing. An inlet 12 is suitably arranged to supply air to the interior of cylinder 2 for scavenging said cylinder at the end of the piston stroke, said inlet also operating to break the suction on the carburetor until the piston passes the air inlet on its return stroke during which the gaseous mixture is compressed. Reciprocably mounted 75 in the cylinder 2 is a piston 13 within which one end of an endwise-movable rod 14 is rotatably mounted by means of ball bearings 15.

As shown in Figures 1 and 3, the rod 14 is provided with helical ribs 16 which operate in helical guide-ways 17 formed in the hub 18 of a fly-wheel 19, said fly-wheel being supported by ball bearings 20 mounted in axially spaced standards 21, 22. The standards 21, 22 are presented upwardly from a common base plate 23. The forward end of helical rod 14 carries a cross-head block 24, said cross-head block being provided with two pairs of oppositely presented journal pins 25. Journalled upon said pins 25 are rollers 26 which operate between angular guide rails 27 which constitute a cross-head guide mounted on one end of a rotary shaft 28. By means of this construction, helical rod 14 is connected to the rotary shaft 28 by means of an axially slideable non-rotary connection. The rotary shaft 28 may carry a fly wheel 29 which is keyed thereto by a key 30. Said rotary shaft 28 is journalled in a standard 31 and carries a bevel pinion 32 meshing with a bevel gear 33, keyed to the lower end of a short shaft 34, said shaft 34 being rotatably mounted in a bearing block 35 carried by pedestal 31.

Keyed to the upper end of shaft 34 is a bevel gear 36 which meshes with a large bevel gear 37.

37 secured to the lateral face of a fly wheel 38, said fly wheel being rotatably mounted on the rotary shaft 28 by means of ball bearings 39. Bolted to the other face of fly wheel 38 is the circular flange 40 of a power drum 41, the other end of said power drum being provided with a reduced portion which is journaled at 42 within the standard 21 and rotatably supported by a sleeve portion 27^a 10 of the cross head guide by means of ball bearings 43. Power drum may be adapted as the support for a power-transmitting device such, for example, as a pulley, or it may be made to serve as the mount for an electric generator 15 armature.

A suitable starting device may be provided in the form of a self-starting motor 44 provided with an armature shaft 45 which carries at its outer end a spur pinion 46, said 20 spur pinion meshing into a ring gear 47 carried by the fly wheel 38. The operation of my improved engine will now be readily understood, and briefly described is as follows:

Energizing the self-starting motor 44 25 serves to set in motion fly wheel 38, which operates through spur gears 37, 34, 33 and 32 to rotate shaft 28 and through its connections with helical rod 14 to set the fly wheel 19 in motion. A retardation in the motion of fly 30 wheel 38, by reason of the load falling thereon, will bring about a relative acceleration of fly wheel 19, with the result that the helical rod 14 is operated by its helical connection with hub 18 to move the piston 13 toward the 35 right. A succeeding explosion within cylinder 2 imparts a movement to piston 13 toward the left under the expansion of the motive power mixture contained in said cylinder. During this endwise movement of helical rod 40 40 through the hub 18 of fly wheel 19, said rod is made to rotate relatively to said fly wheel 19 and under the driving impulse of piston 13, imparts to the fly wheel 29 a rotary speed that is greater than that at which fly 45 wheel 19 is rotating at any given instant. At the same time, fly wheel 19 suffers a retardation in its speed until at the end of the piston stroke the momentum of fly wheels 29 and 38 is applied to an acceleration of fly wheel 19 50 which by reason of this impulse and consequent retardation in the speed of fly wheels 29 and 38, will by its momentum surpass in speed the fly wheel 29. The immediate result of this movement is to return the helical rod 14 to initial position in readiness for a 55 new power-driven stroke under an increased speed of fly wheel 19.

It will be understood from the foregoing 60 description that an internal combustion motor constructed in accordance with the principles of the present invention will have the following advantages. The fuel intake as well as the cylinder-scavenging operations take place under a sustained substantially 65 constant suction due to a motor-driven fan

operated at substantially constant speed. Ignition takes place under the action of a continuously heated grid or hot-point system which requires no timing control such as that employed in connection with a spark-plug. Under these conditions, a carburetor may be used which is simple in construction and operation. Furthermore, it becomes possible to drive the piston with a very lean 70 gaseous mixture. Inasmuch as the drive 75 thrust operates axially of the helical rod and thru the center of the piston, there will be no side thrust upon said piston. By means of the construction described above and shown on the drawings, the speed of the 80 motor as well as the degree of compression in the cylinder may be changed as required while at the same time the degree of compression is made independent of the speed 85 of the engine.

I claim:

1. In a device of the character described, the combination with a rotary support provided with a helical guide-way extending therethrough, of a rod movable endwise through said rotary support, said rod being provided with a helical rib operating in said helical guide-way, a rotary shaft coaxially arranged with respect to said rod, and a non-rotary reciprocatory connection between 90 said rod and shaft.

2. In a device of the character described, the combination with a rotary support provided with a helical guide-way extending therethrough, of a rod movable endwise through said rotary support, said rod being provided with a helical rib operating in said helical guide-way, a rotary shaft coaxially arranged with respect to said rod, a non-rotary reciprocatory connection between said 100 rod and shaft, and means rotatably engaging said rod for imparting thereto an endwise movement through said helical guide-way.

3. In a device of the character described, the combination with a rotary support provided with a helical guide-way extending therethrough, of a rod movable endwise through said rotary support, said rod being provided with a helical rib operating in said helical guide-way, a rotary shaft coaxially arranged with respect to said rod, a non-rotary reciprocatory connection between said rod and shaft, a power-transmitting drum, and power connections between said rotary 110 shaft and power-transmitting drum.

4. In a device of the character described, the combination with a power-driven rod provided with a helical rib, said rod being movable endwise, of a support therefor, said support being provided with a rotary helical guide movably-engaging said helical rib for rotating said rod by means of its endwise movement therethrough, and a rotary shaft coaxial with said power-driven rod, said rod 120 125 130

and rotary shaft being provided with non-rotary reciprocatory connections.

5. In a device of the character described, the combination with a power-driven rod 5 provided with a helical rib, said rod being movable endwise, of a rotary support therefor, said support being provided with a helical guide for rotating said rod by means of its endwise movement therethrough, a rotary shaft coaxial with said power-driven rod, said rotary shaft being provided with a cross-head guide presented towards said rotary support, and a cross-head carried by said rod and reciprocable in said cross-head 10 guide.

6. In a device of the character described, the combination with a power-driven rod provided with a helical rib, said rod being movable endwise, of a rotatably-supported 20 guide for said helical rib whereby said rod is rotated during its endwise movement therethrough, a rotary shaft coaxial with said power-driven rod, said rod and rotary shaft being provided with an axially-slidable 25 non-rotary connection, and a reciprocatory piston rotatably connected to said rod.

7. In a motive-power device, the combination with a cylinder, of a piston reciprocable in said cylinder, a rotary fly wheel, a rod 30 movable endwise through the hub of said fly wheel and having threaded connections therewith, a rotary shaft coaxially alined with said rod, a cross-head guide carried by said rotary shaft, a cross-head carried by 35 said rod and reciprocable in said cross-head guide, a second fly wheel coaxial with said rotary shaft, and geared connections between said rotary shaft and the second-mentioned fly wheel.

40 8. In a motive-power device, the combination with a cylinder, of a piston reciprocable in said cylinder, a rotary fly wheel, a rod movable endwise through the hub of said fly wheel and having threaded connections therewith, 45 a rotary shaft coaxially alined with said rod, a cross-head guide carried by said rotary shaft, a cross-head carried by said rod and reciprocable in said cross-head guide, a second fly wheel coaxial with said rotary shaft,

50 geared connections between said rotary shaft and the second-mentioned fly wheel, and a drum mounted on said second fly wheel and extending axially around said cross-head guide.

55 9. In a motive-power device, the combination with a cylinder, of a piston reciprocable in said cylinder, a rotary fly wheel, a rod movable endwise through the hub of said fly wheel and having threaded connections therewith, 60 a rotary shaft coaxially alined with said rod, a cross-head guide carried by said rotary shaft, a cross-head carried by said rod and reciprocable in said cross-head guide, a second fly-wheel coaxial with said rotary shaft, 65 geared connections between said rotary shaft and the second-mentioned fly wheel, a drum mounted on said second fly wheel and extending axially around said cross-head guide, and a bearing support interposed between the first-mentioned fly 70 wheel and said drum for journalling the free end of said drum.

75 10. In a device of the character described, the combination with a rotary fly wheel, of a power-driven rod movable endwise through the hub of said fly wheel, said rod being provided with helical threaded connections with the hub of said fly wheel, a rotary shaft coaxial with said fly wheel and power-driven rod, 80 relatively-slidable non-rotary connections between said rod and rotary shaft, and a second fly wheel connected to and driven by said rotary shaft.

85 11. In a device of the character described, the combination with a rotary fly wheel, of a power-driven rod movable endwise through the hub of said fly wheel, said rod being provided with helical threaded connections with the hub of said fly wheel, a rotary shaft coaxial with said fly wheel and power-driven 90 rod, said rotary shaft being provided with a cross-head guide presented towards said fly wheel, a cross-head carried by said rod and reciprocable in said cross-head guide, a second fly wheel coaxial with said rotary shaft, 95 and geared connections between said rotary shaft and the second-mentioned fly wheel.

JAMES F. LEAHY.
